W. C. WHITE

SYSTEM FOR PRODUCING OSCILLATIONS

Filed Jan. 20, 1921

Inventor:
William C. White,
by *John G. Davis*
His Attorney.

UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

SYSTEM FOR PRODUCING OSCILLATIONS.

Application filed January 20, 1921. Serial No. 438,560.

To all whom it may concern:

Be it known that I, WILLIAM C. WHITE, a citizen of the United States, residing at Schenectady, in the county of Schenectady, 5 State of New York, have invented certain new and useful Improvements in Systems for Producing Oscillations, of which the following is a specification.

My present invention relates to the production of electrical oscillations, and more particularly to the production of such oscillations in a radio transmitting system.

The first object of my invention is to provide a simple and efficient system for producing high frequency oscillations which will be particularly adapted for operation over a wide range of frequencies and which will require a minimum number of adjustments for securing the most efficient operation over the same range of frequencies.

In many of the oscillating systems employing electron discharge devices for producing and transmitting by radio high frequency oscillations, which have previously been employed, it has been customary to employ the transmitting antenna as the oscillating circuit and to derive the energy necessary for exciting the grid to maintain oscillations directly or indirectly from the 25 antenna system. In the operation of such systems three adjustments have been necessary to obtain good efficiency in operation, namely:—

- (1) Adjustment of antenna inductance for 35 desired wave length;
- (2) Adjustment of the ratio of transformation between the antenna and the electron discharge device;
- (3) Adjustment of grid coil and of coupling 40 between antenna and grid circuit to vary the phase and voltage of the energy supplied to the grid to maintain oscillations.

Because of the fact that these adjustments are more or less dependent upon one another a more or less "cut and try" process is necessary in order to secure the desired output and operating efficiency. For example, the third adjustment depends upon the first two because of the fact that the grid excitation is dependent upon antenna current and any adjustment which changes the antenna current will necessitate a change in

the third adjustment to secure the best results.

A second object of my invention is to provide a system in which the third adjustment mentioned will be unnecessary over a wide range of frequencies.

In attaining the objects of my invention I provide a coupling to the grid circuit from the portion of the plate circuit which supplies energy to the oscillating system. When the system is operating at rated output, the current voltage relations in this portion of the plate circuit are the same regardless of the frequency generated or the constants of the antenna as these conditions are fixed by the second adjustment. No readjustment of the coupling to the grid circuit with change in antenna constants is necessary therefore to obtain the desired phase relation and voltage of the energy supplied to the grid circuit, once it has been adjusted to one antenna system.

The novel features which I believe to be characteristic of my invention are set forth with particularity in the appended claims; the invention itself, however, both as to its organization and method of operation will best be understood by reference to the following description taken in connection with the accompanying drawing in which I have illustrated diagrammatically one way in which my invention may be carried into effect.

I have indicated in the drawing an electron discharge device having the usual filamentary cathode 2, anode 3, and grid 4. The anode 3 is connected to an inductance 5, a portion of which is in circuit with the 90 antenna 6, variable connections 7 and 8 being provided for varying the coupling between the electron discharge device and the antenna, and for varying the amount of inductance, and hence the tuning of the antenna. The cathode 2 of the device may be grounded at 9 so that the antenna circuit is coupled to a shunt circuit between the cathode and anode and forms the oscillating circuit of the system. Energy for the operation of the system is supplied by means of a source 10, which is connected in a circuit between cathode and anode, which is separate from the antenna circuit and the shunt

circuit between cathode and anode. This circuit contains inductance 11 which is closely coupled to inductance 12 in the circuit between cathode and grid. This grid 5 circuit may also include the usual grid condenser 13 and the grid leak 14. A stopping condenser 15 is inserted in the connection between anode and antenna in order to prevent short-circuiting of the source 10.

10 In the operation of the system the tuning of the antenna may be accomplished in any desired way as by varying the connection 8 and the coupling between the device and the antenna may be adjusted by varying 15 the connection 7. A system of this sort will ordinarily be operated at a certain rated output and by making the two adjustments described this rated output may be obtained for the wave lengths desired. Since the circuit 20 by means of which energy is supplied to the grid system is independent of the oscillating circuit the current voltage relations in this circuit will be substantially constant irrespective of the constants of the antenna. The energy supplied to the grid 25 circuit for maintaining oscillations is dependent upon the variations of voltage on the plate and when the plate to antenna ratio is correctly made will therefore remain substantially constant over a wide range of 30 wave lengths and the phase of the energy thus supplied will also be substantially constant. As a result no change in the coupling 35 between the plate circuit and the grid circuit will be required in order to secure the desired results.

While I have illustrated and described only one embodiment of my invention it will be obvious that my invention is by no 40 means limited to the particular embodiment indicated, but that many modifications in the circuit connections employed may be made without departing from the scope of my invention as set forth in the appended claims.

45 While I claim as new and desire to secure by Letters Patent of the United States, is:—

1. The combination in a system for producing electrical oscillations of an electron 50 discharge device having a cathode, an anode and a grid, an oscillating circuit coupled to a shunt circuit between cathode and anode, a second circuit connected between cathode and anode containing a source of energy, 55 a circuit between cathode and grid and a coupling between the second circuit between cathode and anode and the circuit between cathode and grid, the frequency of the oscillations produced being determined principally by the constants of said oscillating circuit.

60 2. The combination in a system for producing electrical oscillations of an electron discharge device having a cathode, an anode and a grid, an oscillating circuit coupled

to a shunt circuit between cathode and anode, a second circuit connected between cathode and anode containing a source of energy and an inductance, a circuit between cathode and grid and a coupling between the inductance in the second circuit between cathode and anode and the circuit between cathode and grid, the frequency of the oscillations produced being determined principally by the constants of said oscillating circuit.

3. The combination in a system for producing electrical oscillations of an electron discharge device having a cathode an anode and a grid, an oscillating circuit coupled 80 to a shunt circuit between cathode and anode, a second circuit connected between cathode and anode containing a source of energy and an inductance and a circuit between cathode and grid containing an inductance which is coupled to the inductance in the second circuit between cathode and anode, the frequency of the oscillations produced being determined principally by the 85 constants of said oscillating circuit.

4. The combination in a system for producing electrical oscillations of an electron discharge device having a cathode, an anode and a grid, an oscillating antenna associated 95 with a shunt circuit between the cathode and anode, a separate circuit between cathode and anode containing a source of energy, a grid circuit and means for supplying to the grid circuit from the separate circuit between cathode and anode energy 100 for maintaining oscillations in the system, the energy thus supplied being independent of the constants of the antenna and the frequency of the currents generated and the frequency of the currents generated being 105 determined principally by the constants of the antenna.

5. The combination in a system for producing electrical oscillations of an electron discharge device having a cathode, an anode and grid, an oscillating antenna associated with a shunt circuit between the cathode and an anode, a separate circuit between cathode and anode containing a source of energy and an inductance, a grid circuit and means for supplying to the grid circuit from the inductance in the separate circuit between cathode and anode energy for maintaining oscillations in the system the frequency of which are determined principally by the 110 antenna constants, the energy thus supplied being independent of the constants of the antenna and the frequency of the currents generated.

115 6. The combination in a system for producing electrical oscillations of an electron discharge device having a cathode, an anode and a grid, an oscillating antenna associated with the cathode and anode, a separate circuit between cathode and anode containing 120

a source of energy, a grid circuit, said circuits being closely coupled in order to supply to the grid circuit from the separate circuit between cathode and anode energy 5 for maintaining oscillations in the system the frequency of which are determined principally by the antenna constants, the

energy thus supplied being independent of the constants of the antenna and the frequency of the currents generated. 10

In witness whereof, I have hereunto set my hand this 18th day of January 1921.

WILLIAM C. WHITE.
